(57) CLAIM

The ornamental design for a set of pumpkin lanterns, as shown and described.

DESCRIPTION

FIG. 1 is a Front view of a set of pumpkin lanterns showing my new design;

FIG. 2 is a Rear view thereof;

FIG. 3 is a Left side view thereof;

FIG. 4 is a Right side view thereof;

FIG. 5 is a Top plan view thereof;

FIG. 6 is a Bottom plan view thereof; and,

FIG. 7 is a Perspective view thereof.

The broken lines shown in the drawings illustrate portions of the set of pumpkin lanterns that form no part of the claimed design.

1 Claim, 7 Drawing Sheets
